UNITED STATES PATENT OFFICE.

JOHN K. HOLBROOK, OF NEWARK, NEW JERSEY, ASSIGNEE TO GEORGE MURPHY, INC.,
OF NEW YORK, N. Y.

FOREGROUND RAY-SCREEN.

988,710.

Specification of Letters Patent. Patented Apr. 4, 1911.

Application filed June 8, 1910. Serial No. 565,700.

To all whom it may concern:

Be it known that I, JOHN K. HOLBROOK, a citizen of the United States, and a resident of Newark, in the county of Essex and State of New Jersey, have invented a new and Improved Foreground Ray-Screen, of which the following is a full, clear, and exact description.

This invention relates to a foreground ray screen for cameras or other picture-taking devices.

It is a well known fact that in taking photographs of landscapes on a bright sunny day, the bright blue of the sky affects the sensitive plate or film ten or more times as quickly as the grass and trees, so that generally an overexposed picture of the clouds is necessary, to obtain good detail of the grass and trees, or, on the other hand, the under-exposure of the grass and trees is necessary, in order to obtain a detail exposure of the clouds and sky.

An object, therefore, of this invention is to provide a device which will retard those rays which act on the sensitized plate or film quickest, and thereby obtain a photograph in which the detail throughout will be just right.

A further object of this invention is to provide a device which will be simple in construction, inexpensive to manufacture, strong, durable, and readily adjusted.

These and further objects, together with the construction and combination of parts, will be more fully described hereinafter and particularly set forth in the claims.

Reference is to be had to the accompanying drawings forming a part of this specification, in which similar characters of reference indicate corresponding parts in all the views, and in which—

Figure 1 is a front view in elevation of one form; Fig. 2 is a vertical section through the screening member of either form; Fig. 3 is a front view in elevation, partly in section, of another form; and Fig. 4 is a vertical section through the form illustrated in Fig. 3.

Referring more particularly to the separate parts, 1 represents a holder of any form suitable to fit over the end of the lens hood of a camera, and may be removably secured thereto by a plurality of inwardly-extending spring grips 2 provided with rubber covers 3. The holder is provided, in both forms, with a filter or screening member 4, which

in the case of the form illustrated in Fig. 1 is immovable and preferably of a circular shape. In both forms, the filtering member 4 consists, as will be more clearly seen by reference to Fig. 2, of a pair of sheets 5 and 6 of any suitable transparent material, such as glass, having parallel faces spaced apart by a layer or film of colloidal material 7, such as cement, said layer of cement containing a coloring matter of a yellowish or amber tint.

It will be noted that the layer 7 is wedge-shaped, being thickest at the top and tapering gradually downward to microscopic thinness at the bottom. The difference in thickness of this colored cement is sufficient to give a screen of the required colored density at the top and of the required clearness at the bottom, with a gradual variation between the top and the bottom. The thickness, however, of the cement layer, even at its thickest point at the top is about eight to ten thousandths of an inch, so that this wedge shape, while giving the desired color variation, does not produce any undesirable prismatic effect.

In the case of the form shown in Fig. 3, the variation in color effect is spread out over a distance considerably greater than the dimensions of the lens to which the device is applied, and the screening member is made adjustable, so that any portion thereof can be brought into co-operative relation with the lens, thus adapting the device to be adjusted to various conditions where greater or less screening effect is desired. For this purpose, the holder 1 is extended on either side, and is provided with bent-over flanges 8, which form ways between which the screening member 4 is adapted to slide. The ways themselves may be sufficiently tight to hold the screening member in any adjusted position, or an auxiliary spring 9, concealed within one of the ways, may be provided for this purpose.

While I have shown two embodiments of my invention, I do not wish to be limited to the specific details thereof, but desire to be protected in various changes, modifications and alterations which I may make within the scope of the appended claims.

Having thus described my invention, I claim as new and desire to secure by Letters Patent:

1. A ray screen for a camera, adapted to

- modify the action of the light coming there-
through, comprising a plurality of sheets of
transparent material, and a layer of cement
interposed between said sheets and adapted
5 to secure said sheets together, said layer
tapering gradually from one edge of the
sheets to the opposite edge.
2. A ray screen for a camera, adapted to
modify the action of the light coming there-
10 through, comprising a plurality of sheets of
transparent material, and a layer of cement
interposed between said sheets and adapted
to secure said sheets together, said layer
tapering gradually from one side to the
15 other, and having a ray-filtering coloring
therein.
3. A ray screen for a camera, adapted to
modify the action of the light coming there-
20 through, comprising a plurality of sheets of
transparent material, and a layer of col-

loidal material interposed between said
sheets, said layer tapering gradually from
one side to the other.

4. A ray screen for a camera, adapted to
modify the action of the light coming there-
25 through, comprising a plurality of sheets of
transparent material, and a layer of col-
loidal material interposed between said
sheets, said layer tapering gradually from
one side to the other, and having a ray-filter-
30 ing coloring, whereby certain rays of light
have their rate of travel changed in passing
through the screen.

In testimony whereof I have signed my
name to this specification in the presence of 35
two subscribing witnesses.

JOHN K. HOLBROOK.
